PLUGBOARD CONTACTOR

James M. Cunningham, Endicott, N.Y., assignor to International Business Machines Corporation, New York, N.Y., a corporation of New York

Application December 21, 1951, Serial No. 262,768

4 Claims. (Cl. 339—18)

This invention relates to an improved contactor for use in the plugboard or circuit connecting panels of electric accounting machines.

In the contactor devices of the prior art various detailed structures are utilized to obtain an electrical connection between electrical contactors. It is, therefore, the principal object of this invention to provide an improved and simplified contactor arrangement to the end that better electrical contact will be obtained between the contacting elements.

A further object of the invention is to provide means by which a contactor can readily be inserted in a correct position in a plugboard panel and be retained in this correct position.

A still further object is to cause an improved wiping action of the contacting elements.

Another object is to reduce the cost of making a contactor through the improved structure of this invention.

Briefly, the contactor of this invention is utilized in a plugboard panel and comprises a body portion having a plurality of wing sections and a spring tongue having a plurality of wing sections at one extremity. The tongue is folded under the body portion and protrudes beyond the marginal surface of the body portion. The wing sections of the body portion form a barrel which envelops the tongue and is concentric with the wing sections of the tongue. A pair of locking lugs is formed by slots in the body portion and extends from the barrel. A resilient member is formed by a U-shaped incision in the body portion and projects above the barrel. This resilient member is so constructed and arranged as to cooperate with the locking lugs whereby the contactor can be snapped into a fixed position on the panel. A contact making terminal is carried at the protruding end of the tongue for making an electrical connection with a mating contactor.

Other objects of the invention will be pointed out in the following description and claims and illustrated in the accompanying drawings, which disclose, by way of examples, the principle of the invention and the best mode, which has been contemplated, of applying that principle.

In the drawings:

Fig. 1 is a section through the contactor showing it in the fixed plugboard in cooperative relationship with an existing contactor in the movable plugboard.

Fig. 2 is a surface development of the improved contactor for the stationary panel.

Fig. 3 is a perspective view of the contactor showing it rolled up into the desired shape for entry into a position in the stationary panel.

Fig. 4 is a sectional view of the contactor along lines 4—4 of Fig. 1.

Fig. 5 is a section along lines 5—5 of Fig. 1.

Fig. 6 is a section along lines 6—6 of Fig. 1.

Fig. 7 is a section along lines 7—7 of Fig. 1.

The contactor of the present invention can be utilized in various plugboard arrangements, but for purposes of illustration, it is shown herein as applied to a plugboard for electrical accounting machines of the type disclosed

2

in the patent to C. D. Lake, No. 2,111,118, granted March 15, 1938, in which there is provided a fixed plugboard containing rows and columns of spring contactors and an insertable plugboard in which there are corresponding rows and columns of companion contactors fixedly secured to this board. This latter board is arranged to be swung into engagement with the first board so that electric contact is effected between oppositely located contactors on the two boards.

10 Referring to Fig. 1, 9 represents the fixed plugboard panel similarly identified in the patent, and 10 represents the removable plugboard panel also so identified in the patent.

15 In each opening through the fixed panel 9 there is inserted a contactor 11. As disclosed in the surface development of Fig. 2, the contactor 11 includes a spring tongue or finger portion 12 having a pair of rectangular resilient wing sections 13 and 14 at one extremity and a rounded contact making terminal 15 at its other extremity. The body portion of the contactor which is shaped to form a barrel 16 (Fig. 3) comprises a pair of rectangular resilient wing sections 17 and 18. All of the wing sections extend outwardly in a direction transverse to the longitudinal axis of the contactor, and are 20 formed by the cut-outs or notches 19 extending inwardly from the longitudinal marginal edges of the contactor. Wing sections 17 and 18 are preferably divided into a plurality of portions, and these will be described later in detail.

25 30 When the development in Fig. 2 is fashioned or formed into the desired shape as illustrated in Fig. 3, the pair of wing sections 13 and 14 form a cylindrical supporting member for spring tongue 12 (see Figs. 6 and 7), and the wing sections 17 and 18 form the barrel of the contactor generally designated 16.

35 Each of the wing sections 17 and 18 is provided with a locking lug 20 and 21, respectively, which is adapted to engage a groove 27 (Fig. 6) in the back side of the fixed plugboard panel 9 to position contactor 11 correctly.

40 45 These lugs are formed by the provision of slots 22 which extend inwardly from the marginal sides of wing sections 17 and 18. When the contactor of Fig. 2 is fashioned to the desired shape as illustrated in Fig. 3, the locking lugs 20 and 21 are preferably allowed to remain in a partially extended position with respect to the barrel 16.

Means are provided to assist in retaining the contactor 11 in the opening in fixed panel 9. This is accomplished by a spring catch 23 (Fig. 3) provided on the barrel 16. Spring catch 23 is formed by cutting a U-shaped incision 50 55 24 in the body portion of contactor 11 (Fig. 2) and applying pressure to the metal between the legs of the incision to give it a permanent set on a plane above that of the remaining body portion (Fig. 5). When the contactor is fashioned to the desired shape, the spring catch 23 assumes the position shown in Fig. 3.

It is seen in Fig. 2 that the body portion of the contactor 11 has a concave arcuate marginal portion 25 at one extremity. When the contactor 11 is shaped as shown in Fig. 3, arcuate portion 25 forms an opening, the upper edge of which is offset with respect to the lower edge in barrel 16. This construction allows ample space for spring tongue 12 to adjust itself when it is engaged by a contact prong or contactor 26 of the movable panel 10 (see Figs. 1 and 4).

60 65 70 The method of forming and design of the improved contactor 11 will now be described. The spring tongue 12 is first folded back at line x—x (Fig. 2) under the body portion and given an initial set (not shown). The barrel is then formed around tongue 12, bending it into the position shown in Fig. 3 to give it an initial tension of approximately 4 ounces. On the initial set the tongue 12 projects from the body portion at an angle greater than

the angle which remains when it is bent to the position of Fig. 3 by the forming of the barrel. It should be noted that the lower inside surface of barrel 16 holds tongue 12 at the 4 ounce tension. In moving approximately $\frac{3}{32}$ of an inch as a prong 26 of the movable panel is engaged as shown in Fig. 1, the tension on spring tongue 12 is increased to approximately $7\frac{1}{2}$ ounces. The existing contactors of the prior art undergo a change in tension from 0 to approximately 1 pound. The smaller change in tension of the contactor of this invention is made possible by increasing the length of spring tongue 12 which is nearly twice the length of the spring arm of the prior art devices. The initial tension on spring tongue 12 has the effect of starting an effective wiping contact action as soon as it is engaged by a prong 26 of the movable panel 10. In the existing contactors a substantial movement is required before the tension becomes large enough to produce an effective wiping contact action.

It is to be noted from Fig. 2 that spring tongue 12 is tapered on its upper and lower longitudinal surface toward terminal 15. This has the effect of equalizing the strain along the spring tongue as the tongue is moved by engagement with prong 26. The result obtained is equivalent to making the tongue of stock having a tapered cross section.

The improved design of this invention allows contactor 11 to be made preferably of sheet brass instead of an alloy of copper which is in use in existing contactors. This facilitates the assembly of the contactor 11 on the fixed panel 9 since the improved contactor merely has to be pushed into a hole in the panel until spring catch 23 snaps up behind the front wall 9a of the panel. Locking lugs 20 and 21 enter grooves 27 (Fig. 6) in the back side 9b of the fixed panel to position the contactor 11 correctly. The old style contactors had a set of lugs which were bent up behind the panel after the contactor was inserted and a set of aligning lugs at the front side of the panel.

While the spring tongue 12 of the new contactor 11 is longer than that of previous contactors, the positioning of the tongue is more accurate because it is supported close to one of its extremities by a portion of barrel 16 (Fig. 1). When spring tongue 12 receives its initial set, wing sections 13 and 14 are folded under wing sections 17 and 18 respectively and form a cylindrical supporting member for spring tongue 12 as shown in Figs. 6 and 7 after barrel 16 is formed. The cylindrical member 13, 14 fits snugly against the inside surface of one end of barrel 16 formed by wing sections 17 and 18. It should be noted that spring tongue 12 engages the roof of barrel 16 for an appreciable distance beyond supporting cylinder 13, 14. The end of the spring tongue is also less subject to being accidentally given a permanent set which will disturb its proper position, because the tongue is anchored at a remote point inside the barrel and its movement is limited by the barrel.

While there have been shown and described and pointed out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. As a new article of manufacture, an electrical contactor for a plugboard panel comprising a body portion having a plurality of wing sections, a spring tongue having a plurality of wing sections at one extremity, said tongue being folded under said body portion and protruding beyond the marginal surface of said body portion, the wing sections of said body portion forming a barrel which envelopes said tongue and is concentric with the wing sections of said tongue, a pair of locking

members formed by slots in said body portion and extending from said barrel, a resilient member formed by a U-shaped incision in said body portion and projecting above said barrel, said resilient member being so constructed and arranged to cooperate with said locking members, whereby said contactor may be snapped into a fixed position on said panel, and a contact making terminal carried at the protruding end of said tongue for making an electrical connection with a mating contactor.

2. A contactor for insertion in an opening in a plugboard panel comprising a body portion having a plurality of wing sections, a spring tongue having a plurality of wing sections at one extremity, said tongue being folded under said body portion, the wing sections of said body portion forming a barrel having an opening extending therethrough which envelopes said tongue and is concentric with the wing sections of said tongue, said tongue being supported at one end by said barrel above the longitudinal axis of the contactor and extending through the opening in said barrel in a direction to cross said axis, a pair of locking members extending from said barrel, a resilient member projecting above said barrel, said resilient member being so constructed and arranged to cooperate with said locking members whereby said contactor may be snapped into a fixed position in the opening in said panel, said tongue engaging the barrel with an initial tension below said axis and protruding from one end of the barrel opening, and a contact making terminal carried at the protruding end of said tongue for making an electrical connection with a mating contactor, the initial tension of said tongue being approximately doubled by said connection.

3. In combination, an electrical contactor, a plugboard panel having an opening therein for receiving said contactor, said contactor comprising a body portion having a plurality of wing sections, a spring tongue having a plurality of wing sections at one extremity, said tongue being folded under said body portion and protruding beyond the marginal surface of said body portion, the wing sections of said body portion forming a barrel which envelopes said tongue and is concentric with the wing sections of said tongue, a pair of locking lugs extending from said barrel, a pair of grooves in said panel for receiving said lugs, a resilient member projecting above said barrel, said resilient member being so constructed and arranged to hold said lugs in said grooves whereby said contactor may be snapped into a fixed position in the opening of said panel, and a contact making terminal carried at the protruding end of said tongue for making an electrical connection with a mating contactor.

4. In a machine having a fixed plugboard panel and a removable panel, the combination of a contactor secured in a fixed panel, a second contactor secured in the removable panel, said first named contactor comprising a body portion having a plurality of wing sections, a spring tongue having a plurality of wing sections at one extremity, said tongue being folded under said body portion and protruding beyond the marginal surface of said body portion, the wing sections of said body portion forming a barrel which envelopes said tongue and is concentric with the wing sections of said tongue, a pair of locking lugs extending from said barrel, a pair of grooves in said fixed panel for receiving said lugs, a resilient member projecting above said barrel, said resilient member being so constructed and arranged to hold said lugs in said grooves whereby said contactor may be snapped into a fixed position in said fixed panel, said tongue being held with an initial tension against the lower inside surface of said barrel, and a contact making terminal carried at the projecting end of said tongue for engaging said second contactor, the tension on said tongue being increased to twice its initial value by said engagement.
